US0D1101021S

(12) **United States Design Patent** (10) **Patent No.:** **US D1,101,021 S**
(45) **Date of Patent:** **** Nov. 4, 2025**

(54) **SURGICAL GOGGLES**

(71) Applicant: **MarketHATCH Co., Inc.**, Akron, OH (US)

(72) Inventor: **Paul A. Joyce**, Sharon, OH (US)

(73) Assignee: **MarketHATCH Co., Inc.**, Akron, OH (US)

(**) Term: **15 Years**

(21) Appl. No.: **29/959,715**

(22) Filed: **Aug. 27, 2024**

(51) LOC (15) Cl. **16-06**

(52) U.S. Cl.

USPC **D16/314**; D16/101; D16/312

(58) **Field of Classification Search**

USPC D24/110-110.6, 108, 162, 164, 189;

(57) **CLAIM**

The ornamental design for surgical goggles, as shown and described.

DESCRIPTION

FIG. 1 is a right perspective view;

FIG. 2 is a left perspective view;

FIG. 3 is a front view;

FIG. 4 is a rear view;

FIG. 5 is a top view;

FIG. 6 is a bottom view;

FIG. 7 is a right side view; and,

FIG. 8 is a left side view.

1 Claim, 1 Drawing Sheet
